UNITED STATES PATENT OFFICE.

THOMAS WM. VICTOR WEBB, OF MACLEOD, ALBERTA, CANADA.

BOTTLE-STOPPER.

1,296,444.

Specification of Letters Patent.

Patented Mar. 4, 1919.

Application filed August 10, 1918. Serial No. 249,364.

To all whom it may concern:

Be it known that I, THOMAS W. V. WEBB, a citizen of the Dominion of Canada, residing at Macleod, in the Province of Alberta and Dominion of Canada, have invented 5 new and useful Improvements in Bottle-Stoppers, of which the following is a specification.

This invention relates to a bottle stopper, 10 and one object is to provide means whereby the stopper may be readily removed without injury to the body portion thereof so that the article formed of cork or rubber or other material may be used indefinitely.

15 A further object is to provide a stopper comprising a body portion having a central vertical bore and a device having a head thereon and extending through the bore, the head engaging the lower end of the stopper 20 and a handle member being connected with the upper end of the device passing through the bore.

A still further object is to provide means whereby the handle may be secured at a 25 point below the upper end of the stopper, permitting the handle portion of wire or the like to be placed in the recessed or countersunk portion so that the wire handle member or loop will be out of the way and will 30 not be unintentionally engaged by any object tending to loosen the cork or stopper.

With the foregoing and other objects in view, the invention consists in the novel construction, combination and arrangement of 35 elements hereinafter described and claimed.

In the accompanying drawings:

Figures 1 and 2 are views in vertical section.

Fig. 3 is a vertical section of a modified 40 form.

Figs. 4 and 5 are similar sections of other modified forms.

The stopper formed of any suitable material, such as rubber or cork, comprises a body 45 portion designated 10, having apertured walls, and being provided with a central vertical bore 12 which may be flared toward the lower end as shown at 13, the flared portion being engaged by the tapered shank of the stem 14. A somewhat broad flat head 16 is carried by the lower end of the stem and serves to engage the lower portion of the cork without there being any danger of the stem being pulled through the cork in 55 extracting the latter.

The upper portion of the stem is threaded

as shown at 18 and is engaged by an internal threaded cap or nut 14', which may be countersunk in a recess provided in the upper portion of the stopper. This recess is 60 designated 20, and a washer 21 is dished centrally, the walls 22 engaging the walls of the recess above mentioned. The washer 21 is provided with a central aperture 65 through which the stem 14 passes, in order that the threaded end of the stem may be engaged by the cap or nut 14'. The cap is provided with an aperture 24 through which a wire loop 25 passes, providing a handle member. The wire or other material forming the loop may be placed within the depressed portion of the cap or washer when it is desired to have the loop or handle portion out of the way, so that it will not readily be engaged accidentally by any object 70 likely to loosen the stopper.

In the form shown in Fig. 3 I make use of a disk member 30 provided with an apertured upstanding member 31 to which a wire 32 is secured, this wire passing upwardly 80 through the body portion of the stopper and including two strands which separate and pass through opposite sides of a thin metal washer 33. The wire then extends upwardly to form a loop or handle portion 34. 85

It will be observed that each form of the device is simple in construction and that means are not only provided for removing the stopper, but that the stopper itself is preserved in good condition indefinitely, no 90 undue twisting action or side thrust being necessary in removing the device from the neck of the bottle.

In Fig. 4 the stopper 35 carries a dished member 36 at the upper end thereof provided with a central upstanding member 37 having an aperture transversely thereof for receiving a split ring. This ring is designated 38 and is shown as being in inoperative position. The member 36 is engaged 100 by the threaded stem 39 having a head 40 on the lower end thereof.

In Fig. 5 the dished washer 41 is provided with a channel 42 around its outer edge, in which channel split ring 38' may rest when 105 not in use.

Ring 38, above referred to, rests below the edge of washer 36, in the manner shown in Fig. 4, when not in use.

What is claimed is:

1. In a device of the class described, a 110 body portion having a central bore flared

toward its lower end, a stem located in said bore and having a shank conforming with the flared portion of the bore and including a head engaging the end of the body portion, the upper portion of the body being recessed centrally, the recess communicating with the bore, a washer having a dished central portion projecting into the recess, the outer edges of the washer engaging the top **10** of the body portion, the stem projecting through the dished portion of the washer, a flexible handle member which may be received within the dished portion and a nut having a transverse aperture and a threaded **15** bore, the bore engaging the end of the stem and the transverse aperture providing for securing the handle to the nut and the stem at a point below the edge portion of the

washer, preventing accidental engagement of the handle when within the dished portion. **20**

2. In a device of the class described, a body portion having a central bore, a stem located within the bore and having a head on one end thereof engaging one end of the **25** body portion, said body portion having a recess at the upper end in communication with the bore, a washer having a dished central portion projecting into the recess and being provided with an annular groove portion on its outer edge, a handle member detachably connected with the stem and proportioned to be received within the groove portion when detached. **30**

In testimony whereof I affix my signature. **35**
THOMAS WM. VICTOR WEBB.
